[57] CLAIM

The ornamental design for a container, as shown and described.

DESCRIPTION

FIG. 1 is a side elevational view of a container showing my new design, the opposite side being the same in appearance;

FIG. 2 is a top plan view;

FIG. 3 is a bottom plan view;

FIG. 4 is a top perspective view on a reduced scale; and FIG. 5 is a top perspective view showing a modified form of my new design, the opposite side being the same in appearance.

The broken lines in FIGS. 1, 2, 4, and 5 showing shoulder panels are for the purpose of illustrating environmental structure only.
